GLENN MUFFLY, OF DETROIT, MICHIGAN, ASSIGNOR TO COPELAND PRODUCTS, INC.,
A CORPORATION OF MICHIGAN

REFRIGERATOR CONSTRUCTION

Application filed June 3, 1927. Serial No. 196,164.

This invention relates to refrigerators, and particularly to that type commonly known as iceless refrigerators, in which two or more chambers are provided within the refrigerator cabinet, in one of which is provided a cooling unit, and in the other of which a heat dissipating unit is provided, said units being suitably connected together by tubing or piping.

10 The principal object of the present invention is to provide a construction of the type described wherein the cooling unit and the heat dissipating unit may be removed from the refrigerator without the necessity of breaking any of the joints in the piping between the two units.

Another object is to provide in combination with a refrigerator having a pair of chambers provided with an insulating wall there-between, a cooling unit in one of the chambers, a heat dissipating unit in the other, flexible tubing connecting said units together, and a notch or opening in an exposed edge of said insulating wall for the 20 reception of said tubing whereby said units may be removed from the refrigerator without disconnecting said tubing.

A further object is to provide in combination with a refrigerating cabinet provided 30 with a pair of chambers having an insulating wall therebetween, a cooling unit removably secured in one of the chambers, a heat dissipating unit removably secured within the other of the chambers, flexible 35 tubing connecting the units, and an opening in the insulating wall for the reception of the tubing, a suitable plug being provided for closing said opening about the tubing and so formed that both of said units may be 40 removed from the cabinet without disconnecting the tubing therebetween.

The above being among the objects of the present invention, the same consists in certain features of construction and combinations of parts to be hereinafter described, with reference to the accompanying drawings, and then claimed, having the above and other objects in view.

In the accompanying drawings which illustrate a suitable embodiment of the pres-

ent invention, and in which like numerals refer to like parts throughout the several views,

Fig. 1 is a face view of a refrigerator, with the doors thereof removed, constructed in accordance with the present invention so that the cooling and heat dissipating units may be removed without disconnecting the tubing therebetween.

Fig. 2 is a horizontal sectional view taken on line 2—2 of Fig. 1.

Fig. 3 is a vertical sectional view taken on line 3—3 of Fig. 1 centrally of the cooling unit.

Fig. 4 is a perspective view of the sheet metal supporting member for the rear end of the cooling unit.

Fig. 5 is a horizontal sectional view taken centrally through the filler block in the opening between the upper and lower chambers, showing the manner in which it embraces the tubes connecting the cooling unit to the heat dissipating unit.

In refrigerators of the type described, it is the conventional practice to removably secure both the cooling unit and the heat dissipating unit within the chambers of the cabinet, and provide connections in the tubing or piping connecting the same and passing through the wall therebetween, whereby when it is necessary to remove one or both of the units for the purpose of servicing the same, such connections may be disconnected, leaving the tubing or piping within the cabinet or attached to one of the units upon removal. After such connections have been disconnected one or more times, it invariably results that it is difficult to thereafter reconnect the same to provide an absolutely tight joint, and in view of the cooling medium usually employed, and the principles of operation of the mechanism itself, any leakage through such connections is very disadvantageous. In addition, many of the types of cooling mediums employed in such refrigerators are such as to readily attack the metals commonly used in such connections, with the result that such connections are liable to corrode and thereby increase the difficulty of disconnecting them

90
95
100

and reconnecting them to form a tight joint.

In the present invention I propose to provide a construction wherein the tubing between the cooling unit and the heat dissipating unit is permanently or otherwise secured to the respective units, means being provided whereby the units may be removed from the cabinet without disconnecting the tubing therebetween at any point. This allows the units to be removed for servicing without breaking the joint in the piping at any point, which breakage might induce subsequent leakage of the cooling fluid from the piping.

In the drawings, I show a refrigerator cabinet 10 having an upper chamber 11 and lower chamber 12, an insulating wall 13 being interposed therebetween. Within the lower chamber 12 and secured to a base 14 removably secured to the bottom thereof by screws, bolts, or other suitable means 15, is a compressor 16, condenser coils 17 and receiver 18. Also removably secured within the lower chamber 12 by bolt screws or other suitable means 18 is a base 19 supporting an electric motor 20 positioned axially in alignment with the coils 17. The armature shaft of the motor 20 is provided with a pulley 21 and a fan 22. The pulley 23 on the compressor 16 is connected to the pulley 21 on the motor armature shaft, for the purpose of driving the compressor 16, by a suitable belt 24, suitable means (not shown) being provided adjusting the tension of the belt. The fan 22 is provided for directing air against the coils 17 for the purpose of cooling the same.

Within the upper chamber 11 is positioned a cooling unit comprising a hollow elliptically shaped member 25 formed of two thicknesses of sheet metal slightly separated from each other between their ends to provide a small space therebetween for the passage of refrigerant therethrough. The rear end of the cooling unit 25 is socketed in the sheet metal supporting member shown in perspective in Fig. 4. This member comprises a main body portion 26 provided with upper and lower rearwardly bent portions 27 terminating in inwardly turned marginal flanges 28 which are secured to the inner rear face of the cabinet 10 by any suitable means such as screws and the like. The side margins of the main body portion 26 are bent forwardly to present flanges 29 between which the cooling unit 25 is adapted to fit, and tongues 30 are struck out of the rearward extending portions 27 and bent forwardly to provide a support for the lower face of the cooling unit 25, and between which tongues the cooling unit is received.

In the body portion 26 below the upper tongue 30 an opening 31 is provided, and a nut 32 is spot welded or otherwise suitably

secured to the rear face of the portion 26 in alignment with the opening 31. The forward end of the unit 25 is supported by an L-shaped bracket 33 secured to and depending from the upper wall of the chamber 11 centrally of the unit 25, a suitable bolt 34 extending through the bracket 33 and unit 25 and being threadably received in the nut 32 on the rear supporting member previously described, the bolt 34 serving to draw the unit 25 up against the body portion 26 and clamping the unit 25 between the bracket 33 and the same.

A suitable metallic housing 35 is provided around the cooling unit 25, the forward face 80 of the same being provided with suitable openings whereby freezing trays 36 may be introduced into the interior of the freezing element 25, there to be supported by the members 37 extending between the opposite 85 sides of the cooling unit 25.

One end of the tubing forming the condensing coils 17 is secured to the discharge end of the compressor 16, and the other end of the tubing is connected to the receiver 18. 90 A tube 38 connects the receiver 18 with the bottom of the cooling unit 25 and another tube 39 connects the top portion of the cooling unit 25 with the inlet side of the compressor 16. The tube 38 immediately below 95 the cooling unit 25 is bent into a goose-neck, and a tray 40 is provided therebelow, whereby any condensation dripping from the cooling unit 25 will be precipitated into the tray 40 and will not be allowed to travel down 100 into the tube 39 into the chamber 11.

The forward face of the insulating wall 13 between the chambers 11 and 12 is exposed, the doors 41 and 42 which close the open ends of the chambers 11 and 12 abutting against the outer edge of the wall 13 in closed position. In the outer edge of the wall 13 is provided a notch 43 for receiving the tubes 38 and 39, a filler member or block 44 being received within the notch 43 about 105 the tubes 39 and 38 for closing the notch 43. The filler block 44 is preferably made of rubber and is split centrally from the forward face thereof, which is adapted to lie flush with the outer edge of the wall 13 110 when in position, to a point adjacent the rear face thereof, suitable openings being provided on the line of split for the reception of the tubes 38 and 39. Upper and lower outwardly projecting flanges 45 are preferably 115 provided on the filler block 44 for contact with the upper and lower face of the wall 13, thereby to prevent misalignment of the liner 44 with respect to the wall 13, and to 120 form a closer joint between the same.

The tubing 38 and 39 is of flexible type as soft copper, easily bendable, and is preferably provided with no joints between the cooling unit 25 and the receiver 17 and compressor 16, respectively. The respective ends 130

of the tubing 38 and 39 may be soldered to the cooling unit 25, and the receiver 18 and compressor 16 respectively, or they may be secured thereto by other suitable means of 5 connection.

The construction provided above allows the cooling unit 25 and the base 14 with the compressor 16, condenser 17 and receiver 18 to be removed from the cabinet 10 with- 10 disconnecting the tubing 38 and 39 either between their ends or at their respective ends. This operation is simply performed by removing the screws or bolts 15 securing the base 14 in position, slipping off the belt 24, 15 withdrawing the filler block 44 from the notch 43 outwardly from the outer edge of the wall 13 and removing the bolt 34, where- upon the cooling unit 25 may be lifted out and placed on the floor, the tubes 38 and 39 20 bending during this operation, and the base 13 may thereafter be slid out. It will thus be seen that both the cooling unit and the heat dissipating unit may be removed without breaking the connecting tubing therebe- 25 tween, this feature allowing the tubing to be permanently secured in place between the units at the factory, and preventing any necessity of breaking the joints in the piping or for providing joints in the piping which, 30 when once broken, may result in a leak. Besides being fool-proof in this respect, the construction provided is simpler and more economical to build than the conventional construction, and more easily assembled and 35 disassembled from the cabinet in which it is secured.

Furthermore, when it is desired to service the machine, it is possible to bodily remove it from the box, substitute another machine 40 and take the defective one to a shop for re- 45 pairs. This removal is made considerably more simple and easy to accomplish because the electrical motor, which is one of the heaviest parts of the machine, is provided 50 on a separate base and need not be removed with the remainder of the machine, thus considerably lightening the assembly to be removed and making possible the removal of most machines by a single workman.

I desire it to be understood that various equivalents for the plug 44, herein described, may be utilized. For instance, a removable piece or plug may extend across the front face of the wall 13, instead of only partially across it and the pipes may be received in cut out portions in either the front of the fixed wall 13 or in the back of the removable piece or plug. My claims are to be construed accordingly.

Formal changes may be made in the specific embodiment of the invention described without departing from the spirit or substance of the broad invention, the scope of which is commensurate with the appended 65 claims.

What I claim is:

1. In a refrigerator, a pair of chambers provided with an insulating wall therebetween, a compressor element and a receiver element in one of said chambers, a cooling element in the other of said chambers, a notch in an exposed edge of said wall, an unbroken pipe connecting said receiver element to said cooling element, an unbroken pipe connecting said cooling element to said compressor element, said pipes passing through said notch, and a removable filler block received within said notch closely embracing said pipes. 70

2. In a refrigerator, a cabinet, a wall therein separating the interior thereof into two chambers, a heat dissipating unit in one of said chambers comprising a compressor, a condenser and a receiver all secured to a unitary removable base, a cooling unit in the other of said chambers, an opening in said wall, a tube passing through said opening connecting said receiver to said cooling unit, a tube passing through said opening connecting said cooling unit to said compressor, and means closing said opening removable from said wall in the direction of the plane thereof whereby said units may be removed from said cabinet without disconnecting said tubes. 80 85 90

3. In a refrigerator, a pair of chambers separated by a wall provided with an exposable edge, a notch in said exposable edge, a cooling unit removably secured within one of said chambers, a heat dissipating unit 100 removably secured within the other of said chambers, tubing connecting said units passing through said notch, and a removable filler block surrounding said tubes and closing said opening, said filler block formed of resilient material centrally split in a vertical plane from its face to a point adjacent the rear edge thereof, and provided with openings on the line of split for reception of said tubing. 105 110

4. In a refrigerator, a moisture collecting cooling unit, a drip pan positioned thereunder, a refrigerant pipe connected to the lower part of said cooling unit above said drip pan and extending laterally over said drip pan, the laterally extending portion of said pipe having a bend therein in the vertical plane, with the lower portion of said bend disposed directly over said drip pan whereby all moisture collecting on the lateral portion of said pipe will be led by gravity into said drip pan. 115 120

GLENN MUFFLY.
